[57] CLAIM

The ornamental design for a saw handle, as shown and described.

DESCRIPTION

FIG. 1 is a right side elevational view of the saw handle showing my new design;

FIG. 2 is a bottom plan view of the saw handle shown in FIG. 1;

FIG. 3 is a left side elevational view of the saw handle shown in FIG. 1 inverted;

FIG. 4 is a top plan view of the saw handle shown in FIG. 1;

FIG. 5 is a butt end elevational view of the saw handle shown in FIG. 1;

FIG. 6 is a blade end elevational view of the saw handle shown in FIG. 1; and,

FIG. 7 is a section view taken along line 7—7 in FIG. 1. The broken line showing of the blade is for illustrative purposes only and forms no part of the claimed design.
